DOOR MAT

Joseph Suskind, Newport News, Va.

Application March 14, 1945, Serial No. 582,667

7 Claims. (Cl. 15—238)

1

This invention, relating as indicated to a door mat is more particularly directed to mats used at the entrance doors of buildings in order to provide some means to remove mud and other adherent dirty materials from the soles of the shoes of a person entering the building.

It is one object of this invention to provide a door mat which is inexpensive to manufacture, easily constructed and which presents a neat, attractive appearance.

It is another object of the invention to provide a door mat which will remove mud and other adherent substances from a person's shoes easily and quickly without damage to the shoes.

It is another object of the invention to provide a mat which in at least two forms can be rolled upon itself so as to consume less space in storage and transit.

It is a major object of the invention to employ waste materials such as the caps normally found on soft drink bottles as the predominant part of a mat. Ordinarily, such bottle caps are thrown away and the cost of salvaging these is, therefore, negligible. Furthermore, it is to be emphasized that the caps form the largest part of the mat and the remaining parts are inexpensive.

It is a still further object of the invention to provide a door mat which can be easily cleaned by means of a brush, broom, or hose. In connection with cleaning, the mat of my invention can be picked up, reversed and dropped, which in practically all cases will remove any dirt which has become lodged in the mat.

Another object of the invention is to provide a door mat of few unit parts; that is, in one embodiment the mat comprises caps and links whereas in the other embodiments, the mat comprises caps, retaining wires and a frame member. To the accomplishment of the foregoing and related ends, said invention, then consists of the means hereinafter fully described and particularly pointed out in the claims.

Fig. 1 is a partial plan view of one embodiment of the mat of my invention.

Fig. 2 is a partial vertical section taken on line 2—2 of Fig. 1.

Fig. 3 is a partial plan view of a modification of the mat shown in Fig. 1.

Fig. 4 is a partial vertical section taken on line 4—4 of Fig. 3.

Fig. 5 is a partial plan view of another modification.

Referring now to the drawings and more particularly Fig. 1, it will be seen that my mat in

2

this embodiment comprises a rectangular frame comprised of members 1 and 2 extending at right angles to each other, these being united to similar members not shown, to form a rectangle. It is, of course, to be understood that the frame may be made in any geometrical form. Wires 3 extend transversely of the mat and are united at their extremities to the parallel walls of the rectangular frame. In this instance, the wires 3 are shown joined to one of the parallel walls 2. Another set of wires 4 extend at right angles to the wires 3 and are similarly joined to the parallel walls of the rectangular frame. As shown in Fig. 2, these wires are joined by welds 10 to the member 1 of the frame but it will be understood that the wires may extend through apertures in the wall 1 or be secured in any other desired manner.

The wires 3 and 4 extend through the upwardly extending flanges 7 of the bottle caps generally indicated at 5. The caps will be apertured and then strung upon the wires. A preferable method of assembly consists in stringing the caps on the wires 3 and then threading the wires 4 through the caps, after which the two sets of wires are joined to the frame member.

The mat consists largely of the bottle caps which are inexpensive since such caps are normally thrown away and constitute waste material. Each of these caps 5 has a bottom portion 8 from which an annular flange 7 extends upwardly, the flange being crimped as shown in Fig. 2. This crimping provides a serrated mud and dirt removing means so that shoes may be very easily and quickly cleaned. The mud or other dirt falls downwardly into the bottle cap or spaces between the bottle caps. If it falls into the cap, the wires tend to prevent caking of the mud if it is in a highly liquid condition, and by simply turning the mat over and dropping the same, it may be thoroughly cleaned of all entrained dirt.

In the modification shown in Fig. 3, the frame member is omitted and the bottle caps 5 are joined by means of wire links 15. These links extend between adjacent flanges of the caps, and of course, entail less expense since less wire is used than in the form shown in Fig. 1. This type of mat may be folded upon itself to form a roll.

In Fig. 5, another embodiment of my invention is shown and in this embodiment, one set of transverse wires 29 are employed, there being no longitudinally extending wires as in Fig. 1. The end member of the frame, preferably, consists of a transverse bar or wall 20 and integral

arms 21 and 22. These arms are connected to links 23 and 24 by pivots 27 and 28 respectively and links 25 and 26 are similarly connected. In this embodiment, the construction is more rugged than that of Fig. 3, yet the mat is foldable so as to require less space in storage.

From the foregoing, it will be seen that I have provided a door mat which is largely composed of waste material, thus greatly reducing its cost. My mat is also inexpensively and easily constructed since it comprises relatively few units which may easily be joined together. In addition to the above advantages, the mat of my invention may be easily cleaned, either by hosing with water, brushing or merely turning the mat over and dropping it.

Other forms may be employed embodying the features of my invention instead of the one here explained, change being made in the form or construction, provided the elements stated by any of the following claims or the equivalent of such stated elements be employed.

This case is a continuation-in-part of my pending application, Serial No. 500,970, filed September 2, 1943, entitled "Floor mats," which has now become abandoned.

I, therefore, particularly point out and distinctly claim as my invention:

1. A door mat comprising a multiplicity of cup shaped bottle cap members and means to secure said members in spaced substantially co-planar relationship; said means including wire members, said cup shaped bottle cap members having flanges that extend upwardly from a closed bottom portion, said wire members extending through apertures in said flanges, said apertures lying below the upper edges of said flanges and above each bottom portion.

2. A door mat comprising a multiplicity of bottle caps and means to secure said caps in spaced substantially co-planar relationship; said means including resilient wire members and said bottle caps having flanges that extend upwardly from a closed bottom portion, said wire members extending through said flanges, said bottle caps being surrounded by a rigid frame member, the extremities of said resilient wires being secured to said frame member.

3. A door mat comprising a multiplicity of bottle caps and means to secure said caps in spaced substantially co-planar relationship; said means including resilient wire members and said bottle caps having flanges that extend upwardly from a closed bottom portion, said wire members extending through said flanges, said bottle caps being surrounded by a rigid frame member of rectangular configuration, said wire members being arranged in sets, with the wires of one set extending transversely to the wires of the other set.

4. A door mat comprising a multiplicity of bottle caps and means to secure said caps in

spaced substantially co-planar relationship; said means including resilient wire members and said bottle caps having flanges that extend upwardly from a closed bottom portion, said wire members extending through said flanges, said bottle caps being surrounded by a rigid frame member of rectangular configuration, said wire members being arranged in sets, with the wires of one set extending transversely to the wires of the other set, the extremities of the wires of each set being secured to parallel walls of said rectangular frame member.

5. A door mat comprising a multiplicity of cup shaped members and means to secure said members in spaced substantially co-planar relationship; said means including wire members and said cup shaped members having flanges that extend upwardly from a bottom portion, said wire members extending through said flanges, and being in the form of links.

6. A door mat comprising a multiplicity of cup shaped members and means to secure said members in spaced substantially co-planar relationship; said means including wire members and said cup shaped members having flanges that extend upwardly from a bottom portion, said wire members extending through said flanges, said cup shaped members being surrounded by foldable frame member, said wire members extending in parallel relationship and being secured at their extremities to portions of said frame member.

7. A door mat comprising a multiplicity of cup shaped members and means to secure said members in spaced substantially co-planar relationship; said means including wire members and said cup shaped members having flanges that extend upwardly from a bottom portion, said wire members extending through said flanges, said cup shaped members being surrounded by foldable frame member, said wire members extending in parallel relationship and being secured at their extremities to portions of said frame member, the portions of said frame member to which said wires are secured being pivotally arranged, whereby said mat may be folded into a roll.

JOSEPH SUSKIND.
